UNITED STATES PATENT OFFICE.

BENNARD TOPMILLER, OF CINCINNATI, OHIO, ASSIGNOR OF TWO-THIRDS
TO SIMON OBERMAYER AND JACOB A. HEINSHEIMER, BOTH OF SAME
PLACE.

CUT-OFF VALVE.

SPECIFICATION forming part of Letters Patent No. 355,628, dated January 4, 1887.

Application filed December 3, 1884. Serial No. 149,424. (No model.)

To all whom it may concern:

Be it known that I, BENNARD TOPMILLER, a citizen of the United States, and a resident of Cincinnati, in the county of Hamilton and 5 State of Ohio, have invented certain new and useful Improvements in Cut-Off Valves, of which the following is a specification.

My invention relates to cut-off valves for steam-engines, and particularly to that class 10 of cut-off valves in which independent laps are employed to control the admission-ports; and it consists of peculiar main and cut-off valves which are balanced at all points of their stroke. It consists, also, of independent laps and means 15 for actuating the same to control the cut-off at any point of the stroke desired, either automatically regulated by the speed of the engine under control of a governor or controlled by the engineer.

20 The invention will be first fully described in connection with the accompanying drawings, and the novel features particularly referred to and pointed out in the claims.

In the accompanying drawings, in which 25 similar reference-letters indicate like parts wherever they occur in the various views, Figure 1 is a vertical sectional view of a steam-chest and valves embodying my improvements, shown mounted in position upon the cylinder, 30 which is shown broken away. The section of the chest and valve in this view is taken through line $x-x$ of Fig. 2. Fig. 2 is an axial section of the steam-chest, taken through line $y-y$ of Fig. 1. Fig. 3 is a side elevation of a 35 steam-engine having the valve-actuating device attached. The valve box and cylinder are shown in vertical section, and the main valve is a modification of the form shown in Figs. 1 and 2. Fig. 4 is an elevation, upon an 40 enlarged scale, of the driving-shaft and the eccentricities which actuate the main and auxiliary valves. This view illustrates a means to vary the point of cut off through a lever under control of the engineer.

45 Referring first to Figs. 1 and 2, the valve-chamber A is in general form cylindrical, and has two heads, a a' , provided with bearings, through which the axes of the valves pass. The valves and valve-chamber are made

slightly tapering, similar to the ordinary plug-valve. The steam is admitted through port a' , and that end of the valve being the larger the pressure of steam will be sufficiently great to keep the valve tight and compensate for wear by use. The main valve B has four 50 points of contact with the case A. These points cover, when the valve is in its vertical position, the ports c c' d d' . There are in the main valve two ports, b b' , one through each end of the valve. These pass each other through 55 the axes of the valve, as seen in dotted line, Fig. 1, and each extends from one of the cylinder-ports c or c' to the port d or d' , diagonally opposite it. In the position shown in Fig. 1 the valve B has just started to admit steam into the cylinder, and has partially uncovered the ports c d for this purpose, and has also commenced to 60 open the ports c' d' for the exhaust from the opposite end of the piston-cylinder. It will be seen by the arrows that steam is admitted 65 back of the piston directly from the chest through port c , and also indirectly through ports d b , while the exhaust is at the same time 70 opened through ports c' c' and b' d' . This provides for a rapid admission and exhaust, and 75 the relief from the steam-pressure being equal upon all sides of the valve B it is equally balanced in every position. The smaller end of the chamber A is counterbored, as shown, so 80 as to prevent forming a shoulder as the circular valve-seat is worn by use. The cut-off or valve C consists of two segmental laps mounted upon arms C' and united by bolts c'' . These arms have inwardly-projecting flanges, upon 85 which the segments C rest. The main valve is oscillated by the shaft b'' , which passes through the tubular bearings of the cut-off valve. The smaller head, a' , has a pocket, a'' , to receive the opposite bearing of the valve B. The pocket has a set-screw passing through it, 90 to bear against the end of the shaft of valve B. The cut-off valve is oscillated by the tubular crank-shaft c' , which has one of its bearings in the head a . The other bearing is in the arm C', at the opposite end of the valve through 95 which the shaft b'' passes.

Referring now to Fig. 3, and assuming that the form of valve shown in Figs. 1 and 2 is

mounted upon the cylinder, I will describe the means by which the valves B and C are actuated. D is a bar, which is fitted to slide in stationary bearings d^2 . One end of this bar is 5 connected to the eccentric E in the usual manner and the other is connected to the crank b^2 of the main-valve shaft b^2 . The bar D and its two connecting-rods operate the main valve B just as the ordinary eccentric rods operate the 10 common slide or rotary valves. F is a bar fitted to slide in bearings f , which are stationary on the bar D. Upon the bar D, and between the two bars D and F, is journaled a cam, G, which has depending from it an arm, g. Upon 15 pins projecting from the inner face of the bar F are two friction-rollers, one upon each side of the cam G. These are shown in dotted lines. The object of the cam G and friction-rollers is to give the bar F motion independent of the 20 bar D; to produce a variable cut-off, which is accomplished by the means now to be described. Projecting up from bar F is an arm, f', which is connected to the crank-arm c' of the cut-off valve C. The crank-pin of the 25 cam-arm g is connected to an eccentric, H, which is fitted to slide around the driving-shaft along-side of the eccentric. The eccentric H has a hub, h, which projects within the flange or rim of a wheel, I, which is secured 30 upon the driving-shaft in proximity to the eccentric. (The hub of the wheel I is removed and the arms or spokes of the wheel I are broken away to expose the parts back of them.) Projecting inwardly from the rim of 35 wheel I are lugs i, and to these are pivoted swinging weights J. The opposite ends of these swinging weights J are connected by rods j to lugs h', which are part of the hub h. It will be seen that as the wheel I revolves 40 the eccentric H will be carried around with it. K are spiral springs which, when the engine is at rest or running at a slow speed, draw the swinging ends of weights J toward the axis of revolution. In this position the 45 eccentrics E and H coincide, and the arm g will be at and remain in the perpendicular position. While the arm g is in this position the arms C' will always be at right angles to the side of the main valve, the relative position 50 of the valves will be maintained, and the cut-off will only occur at full-stroke. As the speed of the engine is increased the weights J will be carried outward by centrifugal force and the relative position of the arms E and H will be 55 changed. Thus when the heavy ends of the arms J are thrown against the rim of wheel i the following lap C will close up against the following ends of the main valve before the admission-port is opened, and no steam will be 60 admitted to the cylinder until the speed of the engine decreases. In the position shown the weights are in a position to cut off at about quarter-stroke of the piston. (The positions of the connecting-rods in Fig. 3 are shown in 65 dotted lines.) In the position shown the piston of the engine has just completed its stroke and the valve B has just commenced to open

the port to admit steam back of the piston. As the valve B is moved by its connecting-rod the eccentric H acts on the bar F, through 70 the cam G, with accelerated motion, and by the time the piston has reached quarter-stroke the following lap C will be closed up against the following end of the valve B, thus cutting off the steam. It will remain in this position 75 until the piston has completed its stroke and the valve has returned to a vertical position, as shown in the drawings. If the speed of the engine is accelerated, the eccentric H will be carried around the shaft in the direction of the 80 arrow and the valve C will be brought against the valve B quicker. If the speed of the engine should be decreased by a diminished pressure of steam, or on account of more machinery being put in motion by it, the weights J will 85 drop inward and the lap C will close against the valve B later, so that more steam will be admitted. It will thus be seen that the supply of steam will be regulated automatically, 90 keeping the engine at uniform speed, whatever the pressure of steam may be, or whatever duty may be required of the engine, and it will also be seen that as steam is admitted to and exhausted from the cylinder simultaneously by two admission and two exhaust ports 95 a greater area for the passage of steam is provided than is possible with the same amount of valve travel in the old form of valves. The crank-governor shown in this figure is no part 100 of my invention. It is old and well known, and is simply used to illustrate the means of automatically regulating the cut-off with my peculiar formation of valve, and any of the well-known crank-governors may be readily applied by any one skilled in the art without 105 invention.

The form of valve shown in Fig. 3 differs from the form shown in Figs. 1 and 2, in having but one opening through the valve to the auxiliary exhaust, and in having laps upon 110 the upper sides of the valve B to prevent steam from the chest passing into the escape-port above.

In Fig. 4 I have shown a means to control the cut-off by a lever. In this view the eccentric-straps are removed and eccentric H is loosely journaled upon the shaft, the same as in Fig. 3. It has projecting from one side a pin, L, which passes through the web of the wheel M. This wheel M has a feather or spline 115 which projects into the spiral groove m in the driving-shaft. It has also a grooved periphery 120 to receive the shoes n, which are pivoted to the forked ends of the lever O, which is pivoted upon the stationary block o. The wheel 125 M is moved back and forth on the shaft by this lever; and as it moves in either direction is partially rotated, carrying with it the eccentric H. The relative positions of the cams E and H are the same as shown in Fig. 3—that is, they are arranged to cut off at about quarter-stroke. When the wheel M is drawn up 130 close to the cam, there is no cut off. When it is drawn back to the position shown in dotted

line, the eccentrics H and E coincide, and arm g of cam G will always remain in the vertical position and the bars D and F move together. The cut-off valve C will therefore remain in- 5 active—that is, it will always be at right angle to it and keep the same relative position. The cut off will then of course be at full-stroke.

The invention herein shown, so far as the tripping mechanism of the main valve and 10 cut-off is concerned, is an improved modification of the tripping mechanism shown in my pending application heretofore filed, and it is evident that these tripping devices may be used interchangeably, whether the valve be 15 a rotary balanced valve, like the one herein shown, or a sliding valve, as shown in my said application.

What I claim as new, and desire to secure by Letters Patent, is—

20 1. The combination, substantially as specified, of a cylindrical steam-chest, an oscillating balanced valve to open the steam-ports, operated directly by the eccentric, and independent cut-off valves upon opposite sides of the 25 main valve and having a movement independent of the main valve, with suitable mechanism, such as shown, to give the cut-off valves an accelerated movement to alternately close said cut-off valves against the following 30 side of the main valve.

2. In a cut-off for steam-engines, the combination of the tapering cylindrical steam-chest, and the tapering oscillating valve, cut away upon opposite sides, as shown, and bearing 35 upon opposite sides of the steam-chest, with the independent cut-off valves upon each side of the main valve and having a movement in-

dependent of said main valve, said main and cut-off valves having common axes, substantially as specified.

3. The combination, substantially as specified, of the cylindrical steam-chest A, having ports d d', with the valve B, having exhaust ports b, and the cut-off valves C, upon each side of the main valve and having a movement in- 45 dependent of it, said main valve being actuated by the eccentric E and its rod, and said cut-off valve being moved independent of the main valve by a bar, F f, controlled by the variable eccentric H, substantially as speci- 50 fied.

4. In a tripping mechanism for cut-off valves, such as described, the combination, substantially as specified, of bar D, mounted to slide in stationary bearings and having its 55 opposite ends connected, respectively, to the eccentric and the main valve, with the bar F f, mounted in bearings secured upon the slide D, having one end connected to the crank-arm of the cut-off valves, and a cam, G, mounted upon 60 bar D and having an arm, g, which is connected to a variable eccentric, as H, and friction-rollers mounted upon the opposite bar, to be engaged by the cam G for the purpose of giving the bar F an accelerated movement to 65 rapidly close the cut-off against the main valve when the variable eccentric is moved in advance of the rigid eccentric, either by the accelerated speed of the engine or by a lever under control of the engineer.

BENNARD TOPMILLER.
